DESIGN FOR A SWINGING GLASS GATE

Samuel F. Cox, Pittsburgh, Pa., assignor to Pittsburgh Plate Glass Company, a corporation of Pennsylvania

Application June 1, 1938, Serial No. 77,471

Term of patent 7 years

To all whom it may concern:

Be it known that I, Samuel F. Cox, a citizen of the United States, residing at Pittsburgh, in the county of Allegheny and State of Pennsylvania, have invented a new, original, and ornamental Design for a Swinging Glass Gate, of which the following is a specification, reference being had to the accompanying drawing, forming a part thereof.

Figure 1 is a front elevational view of a swinging glass gate showing my new design;

Figure 2 is an edge view; and
Figure 3 is a plan view.

The essential features of my design reside in a gate of the type shown comprising a glass panel in combination with the specific finishing channels as shown.

I claim:

The ornamental design for a swinging glass gate, as shown and described.

SAMUEL F. COX.
